JAR REIN SOCKET

Filed Oct. 19, 1927

UNITED STATES PATENT OFFICE

FRANK J. HINDERLITER, OF TULSA, OKLAHOMA

JAR-REIN SOCKET

Application filed October 19, 1927. Serial No. 227,197.

My present invention relates in general to apparatus for removing broken mechanism from wells, and more particularly to a device for removing broken jar parts from a well, which device I have termed a jar rein socket.

In the drilling of wells, the jar employed in connection with the drilling tool is very often broken off in the hole in the well. This 10 usually results in a difficult fishing job, inasmuch as it is practically impossible to get a square or flat-bottomed socket over the broken bails or reins of the jar part remaining in the well due to the fact that the reins 15 are usually rough and lie to one side of the well or hole.

Now I propose to provide a fishing tool comprising a socket and a guide bowl adapted to embrace the broken reins of the jar part 20 remaining in the well sufficiently tight to enable this jar part to be removed or fished from the well.

An object of the present invention is to provide an improved fishing tool adapted to 25 be used to remove a broken jar from a well being drilled.

Another object of my invention is to provide a jar rein socket including means for gripping the reins and a guide tube adapted 30 to align the reins with the jar and adapted to keep the ends or reins of the broken jar from expanding during the pulling operation.

A further object of the present invention 35 is to provide a jar rein socket including a guide tube having an eccentric point adapted to slide with facility between the casing wall and the broken jar reins even when the reins are lying over in the side of the casing, whereby the reins may be aligned with 40 facility with the gripping means of the socket.

Other objects and advantages of my invention will more fully appear from the following detailed description taken in connection 45 with the accompanying drawing, which illustrates a single embodiment thereof and in which:

Figure 1 is a fragmentary vertical section- 50 al view taken through a well casing showing my novel socket in a position ready to grip

the reins of a broken jar, the socket and jar being shown partly in section;

Figure 2 is a sectional view similar to Figure 1 showing the socket device in engagement with the reins of the broken jar; 55

Figure 3 is an enlarged fragmentary sectional view of the socket of my invention;

Figure 4 is an elevation of my novel socket showing the wedges or slips in their uppermost position, the guide tube being shown 60 in section;

Figure 5 is a cross-sectional view taken on substantially the line V—V of Figure 4 looking upwardly; and

Figure 6 is an end view of the device taken 65 on substantially the line VI—VI of Figure 4 looking upwardly.

In the drawings:

Like reference characters designate similar parts throughout the several views. 70

The reference character 10 designates generally the body of my device, which is preferably made of cylindrical rod. The body 10 has formed integral with it a tapered threaded portion 11 adapted to be threaded 75 in the lower end of a suitable tube or rod 12 used to lower the device into the well casing 13.

The body 10 includes a reduced portion 14 defining the shoulder for receiving the upper end of a guide tube 15, which is suitably anchored to the body 10. The tube 15 is disposed concentric with the reduced body portion 14. The lower end of the tube 15 is cut on a slant, as indicated at 16, so as to provide the tube with an eccentric point 17, the 80 purpose of which will be more fully explained hereinafter. The body 10 is provided with a downwardly extending element 18 disposed in the guide tube 15. This element 18 com-

prises a relatively flat piece of metal depending from and formed integral with the body. As best shown in Figures 5 and 6, the element 18 has oppositely disposed concave surfaces 85 19. These concave surfaces, as will more fully appear hereinafter, are adapted to accommodate the reins 20—20 of the broken jar part 21 disposed in the lower part of the casing 13. The jar part 21 comprises an element of a standard jar, such as is well known in the well drilling art. The lower end of 90

95

100

the element 18 is provided with a chisel-like edge 22, which is best shown in Figures 3 and 4. This edge 22 is adapted to engage in the crotch between the reins 20 of the part 21.

5 The member 18 has formed in it two pairs of wedge-shaped slots 23 and 24 disposed near its lower end. The slots 24 are staggered relative to each other, as is evident 10 from Figure 3, whereas the slots 23 are disposed diametrically opposite each other. Disposed in the slots 24 are slideable slips or 15 wedges 25, and disposed in each of the slots 23 is a slideable slip 26. Each of these slips 25 and 26 is provided with a toothed surface 27 (Figure 5), as is evident from the drawing. Each of the slots 24—24, as well as each of the 20 slots 23—23, is of a dovetail shape, as is clearly shown in Figure 5. Each of the wedges is shaped to fit in the associated slot and in reality comprises a dovetail tongue. The 25 slips are slideable in their respective slots and are prevented from falling out of the slots by means of transverse pins 28 secured in the element 18. Each pin 28 extends transversely across the lower end of the associated slot, as is evident from Figure 3.

The operation of my novel fishing tool or socket is briefly as follows:

30 The first thing that is done after the breaking of the jar is to lower the socket of my invention into the well or casing. This socket may be connected to any suitable string of pipe or rod through the means of the 35 threaded portion 11 for the purpose of enabling the device to be lowered into the well. Upon the point 17 of the guide tube 15 coming into the zone of the reins 20 of the broken jar 21, the tube will align the reins with the 40 element 18. Moreover, should the jar reins be in a tilted position, the point of the guide tube will force it back into a vertical position. Thereafter the chisel end 22 of the element 18 forces its way into the space between 45 the reins 20 and its downward motion is arrested by it striking the portion of the jar defining the crotch between the two reins. Of course, it will be understood that during this downward movement of the element 18, the 50 slips 25 are caused to ride upwardly in their respective slots.

Now upon my novel device being raised, the slips will slide down the tapered slip slots or seats and will be wedged between the inner sides of the reins and the element 18. The guide tube 15 will keep the ends of the reins of the broken jar from expanding during the pulling or elevating operation.

55 I desire it understood that although I have illustrated and described in detail the preferred form of my invention, the invention is not to be thus limited, but only in so far as defined by the scope and spirit of the appended claims.

I claim as my invention:

1. In combination, in a fishing tool of the class described, a body member, a downwardly extending element connected to said body member, said element having concave sides shaped to receive the reins of a broken jar in a well, gripping means carried by said element for engaging said reins, whereby the broken jar may be elevated from the well, and a guide tube disposed over said element and connected to said member adapted to fit over said reins and to align them with the concave sides of said element. 70

2. In combination in a fishing tool for removing broken jar members from wells, a body member having a tubular guide portion formed to fit over the reins of the broken jar member, a shank connected to and extending downwardly within said tubular portion, said shank having its sides provided with channels to receive said reins, and wedge means connected to said shank for engaging the reins when they are in said channels to wedge the reins against the wall of said tubular portion. 80

3. In combination in a fishing tool for removing an element from a well having spaced reins, a body, a shank connected to and depending from said body including a spear portion for spreading the reins apart, said shank having its sides provided with channels to receive said reins, and means connected to said shank for wedgingly engaging said reins to enable the element to be thereafter removed from the well with said tool. 90

In testimony whereof I have hereunto subscribed my name at Tulsa, county of Tulsa, Oklahoma.

FRANK J. HINDERLITER.
